DESIGN FOR A PORTABLE RADIO

William J. Schnell, Evanston, Ill., assignor to
Electrical Research Laboratories, Inc., Evans-
ton, Ill., a corporation of Illinois

Application November 14, 1940, Serial No. 96,578

Term of patent 7 years

To all whom it may concern:

Be it known that I, William J. Schnell, a citizen
of the United States, residing at Evanston,
Cook County, Illinois, have invented a new, origi-
nal, and ornamental Design for a Portable Radio,
of which the following is a specification, refer-
ence being had to the accompanying drawing,
forming a part thereof.

Figure 1 is a front perspective view showing
the portable radio of my new design as it appears
with the door panel in open position; and

Figure 2 is a front perspective view as seen
from the other side and showing the door panel
in closed position.

The rear of the portable radio of my new de-
sign is substantially the same as the front shown
in Fig. 2.

I claim:

The ornamental design for a portable radio, as
shown and described.

WILLIAM J. SCHNELL.
